UNITED STATES PATENT OFFICE

JOHN J. BUCKLEY, OF BOSTON, MASSACHUSETTS, ASSIGNOR, BY MESNE ASSIGNMENTS, TO FIREBAR CORPORATION, OF CLEVELAND, OHIO, A CORPORATION OF DELAWARE

FUEL GRATE

Application filed March 17, 1926, Serial No. 95,265. Renewed June 21, 1928.

This invention relates to certain improvements in fuel grates and, more particularly to fuel grates which are primarily designed for the combustion of the more finely divided forms of fuel, such as "pea" and "buckwheat" 5 anthracite coal, screenings and the various forms of bituminous coal.

In the combustion of coal, one of the greatest sources of loss of heat-units arises 10 from failure to supply sufficient air or oxygen to all parts of the fuel mass, so that conditions which approximate to complete combustion may be secured of the gases which are driven off and of the carbon content.

15 While the more finely divided forms of coal may be burned with greater economy and efficiency than the larger sizes, so far as I am aware, prior to my invention, no fuel grate has been produced which will both effectively 20 support the finer forms of coal and will, at the same time, permit air to be supplied in sufficient volume to all parts of the fuel mass to secure even approximately complete combustion thereof. This failure to supply sufficient air to all parts of the fuel mass is 25 largely due to the fact that, while ordinarily approximately one half the total area of a grate surface is open for the passage of air, in grates which are almost universally used 30 the solid portions have flat top surfaces on which the fuel rests and over which the air is prevented from passing by reason of the close contact of this fuel with the grate surface, so that, while air may be supplied 35 in sufficient quantities to fuel directly over the grate openings, it is insufficiently supplied to the other portions of the fuel. Moreover, these grate openings tend to cause concentrated air jets to be directed up through 40 the fuel, which tend to cause holes in the fuel mass, the formation of uncombustible slag and clinkers, and, what is more objectionable, overheating of the grate bars, resulting in warping and burning away the iron of which 45 they are formed.

The objects of my invention are to provide a form of fuel grate which is adapted to support the finer sizes of coal until consumed and which will not permit the passage of un- 50 consumed coal therethru to an appreciable

extent, and will, at the same time, support the coal in a manner to permit air to be conducted to all portions of the fuel mass at the bottom thereof, or at the top surface of the grate, so that air will be supplied to all portions of the fuel in quantities sufficient to secure practically complete combustion thereof. 55 Also to provide a grate which is so constructed that the air passing therethru will have a cooling action thereon and will prevent 60 overheating of any portion thereof.

I accomplish these objects by providing a form of fuel grate which comprises a series of bars each of which is provided at each side thereof with a series of upwardly tapering 65 projections which extend above the top surface of the bar and have fuel supporting faces at their upper ends, said projections being mounted on laterally projecting lugs, fins or flanges which are formed on the sides of 70 the bar and extend downwardly from its top surface for a substantial distance, or to, or nearly to the bottom side thereof, said projections and lugs being cast integrally with the bar, and the fuel being supported above 75 the level of the top sides of the bars, or on the tops of said projections, so that air passing upward between the bars and the lugs on the sides thereof, will pass over the tops of the bars between the projections and upward 80 thru the fuel and will be diffused throughout practically the whole mass. At the same time, heat imparted to the projections, which might be excessive in amount by reason of the direct contact of the fuel there- 85 with, will be conducted to the lugs on the sides of the bars and this heat will be radiated therefrom and taken up by the air passing upward between the lugs and bars, thereby 90 preventing overheating of any portion of 95 the grate.

For a more complete understanding of my invention reference is made to the accompanying drawing in which:

Fig. 1 is a plan view of a stove or furnace grate embodying my invention.

Figs. 2, 3, 4 and 5 are sectional views at lines 2—2, 3—3, 4—4, and 5—5, respectively of Fig. 1.

Fig. 6 is a fragmentary view of the grate in perspective.

According to my invention I provide a frame 10, which, for a stove or small furnace, will be made to fit the bottom of the fire box, and be supported therein in the usual manner, the frame, in the present instance being shown in rectangular form. The entire inner edge portion of the frame 10 is provided with a series of integral, inwardly, and horizontally extending lugs 11, which are regularly spaced apart, providing intermediate vertically extending passages 12. An upwardly extending rib 13 is formed integrally with the frame and extends continuously about the same at the ends of said passages. Said lugs 11 are each provided with an integral, upwardly extending, cubically shaped projection 14, having a flat, horizontally disposed face 15 at its upper end, the faces 15 being all disposed in the same horizontal plane. A groove or horizontal passage 16 is thus formed between the rib 13 and each projection 14, which opens at its inner side to each passage 12 between the lugs 11. The width of the passages 12 is preferably slightly less than the width of said lugs and projections.

The grate, which is adapted to be mounted in the frame 10, comprises a middle longitudinal bar 17, on the ends of which trunnions 18 and 19 are formed, the trunnion 18 being indicated as supported on some part of the stove or furnace, and the trunnion 19 in the frame 10, permitting the grate to be turned to a vertical position. The grate also comprises two longitudinal edge bars 20 and series of parallel cross bars 21, which are spaced equally or arranged at regular intervals from end to end of the grate. All of said bars are cast integral with each other at their points of intersection, and the upper surfaces thereof are disposed in the same horizontal plane. Said edge bars 20 and cross bars 21 are provided with a regular series of pairs of transversely or vertically extending lugs, fins or flanges 22, 26, 27 which project laterally from each side thereof in directly opposite relation, and are cast integrally therewith, and each lug has an integral, trunco-pyramidal-shaped projection 23 extending vertically from the upper portion thereof and directly thereover, three of the sides of each projection being continuous with the corresponding side of the lug, and the fourth side extending from the upper surface of the bar adjacent its edge, so that a space is provided between the adjacent sides of each pair of projections approximately equal to the width of the bar. Said projections are extended above the upper surfaces of the bars a distance, in practice, approximating to the width of the bars, although this distance will be varied according to conditions to be provided for, and the upper

ends thereof are flat, so that a fuel-supporting face 24 is provided on the upper end of each projection, said faces being disposed in the same horizontal plane. Said projections 23 are regularly spaced and arranged in line, both longitudinally and transversely, with each other and with the projections 14 on the frame, so that the width of the spaces between the sides of adjacent lugs, and between the ends of adjacent lugs on adjacent bars, are uniform and approximately equal to the spaces between the lugs 11 on the frame.

As shown in the drawing, the maximum cross sectional area of the lugs 22, 26, 27 and projections 23 is at the level of, or closely adjacent the level of the top side of the bars and the sides of said lugs converge downward from this level to their lower ends and the sides of the projections 23 converge upward from the same level to their upper ends. The sides of the bars also converge from top to bottom. This tapering formation is a practical necessity in forming the entire grate construction in a single integral casting, as shown, the grate being molded from two patterns in separate flasks, the bars and lugs being molded in one flask and the projections 23 being molded in the other, and the construction permitting each pattern to be drawn from the moulding sand, so that when the flasks are placed in together in register these portions may be cast in one piece.

The frame 10 is also similarly formed, and is cast in a similar manner, the frame proper and the lugs 11 thereon having their sides tapering downward from the top surface of the frame and the rib 13 and projections 14 having their sides tapering upward from said surface. The above described tapering formations of the side lugs and projections have, however, important advantages in the practical operation of the grate, as hereinafter described.

With the above described construction, an upwardly extending air passage is provided on three of the sides of each lug and the projection thereon, except when these passages are partly obstructed by the intersection of the longitudinal bars with the cross bars. A horizontally extending passage is also provided between each pair of projections, so that each fuel-supporting face 24 is separated from each adjacent face either by an air passage which leads directly from the ash-pit, or by a passage over the bar, which opens directly to such a passage at both ends and at both sides. Consequently air will be supplied to the fuel supported on each face 24 at all sides thereof, and will, therefore, be directly supplied to all portions of the fuel body. Ash collecting on the faces 24, or on the upper surfaces of the grate bars, will readily slide therefrom into the adjacent air passages and fall into the ash pit, so that the passage of air

over the bars between the projections is unlikely to be blocked with ash to an extent sufficient to interfere with the desired distribution of air beneath the fuel mass, a slight jarring action on the grate usually being sufficient to dislodge the ash and cause it to fall thru the passages between the side lugs into the ash pit, and, as these passages increase in transverse area from the level of the tops 5 of the bars downward, clogging thereof with ash is unlikely to take place. While, in practice, much of the fuel may be of such size that it will be possible for it to fall thru the air passages unconsumed, yet, on account of the 10 fact that the grate surface is broken by the projections, there is a greater tendency for the pieces of fuel to become wedged together, and to arch over the passages, as indicated in Fig. 15 3, than if the entire grate surface was at the same level.

As the fuel is thus practically entirely supported by a relatively large number of small faces, each of which is separated from the next by a passage thru which air is ordinarily 20 free to pass, the air will be practically uniformly distributed throughout the entire area of the grate and, therefore, beneath the entire fuel mass, and as the air will pass upward thru the fuel practically uniformly 25 in all portions thereof correspondingly uniform combustion will be secured throughout the entire fuel mass, and over-heating at certain points by the well known "blow torch" effect of large grate openings will 30 be avoided. Also as the fuel is supported by the projections 23 out of direct contact with the grate bars they do not become over heated and warped or burned out.

While the top faces of the projections 40 and 23 are in direct contact with the fuel and there is, in consequence, a tendency to cause their top portions to be over-heated, this tendency is effectively counteracted, as the construction permits the air passing up 45 between the bars and lugs to pass about all sides of said projections, so that heat radiating therefrom will be imparted to the air and carried upward to the fuel. Also, as said projections taper or decrease in cross 50 sectional area from the tops of the bars upward, and the heat from the fuel is primarily imparted directly to their upper ends, the mass of metal provided to conduct the heat from the top ends of the projections 55 is greater than the mass to which the heat is directly imparted so that the heat is conducted to the grate portions on which the projections are formed, practically as rapidly as it is imparted thereto, under ordinary 60 conditions. Accumulation of heat in the top portions of these projections is thus prevented by providing an increasing cross sectional area of metal for conducting the heat from these portions, and this heat is 65 in turn conducted to the side lugs on which

they are mounted, and also, to some extent, directly to the bars. The lugs, which receive the greater portion of the heat imparted to the projections, are in turn effectively cooled by the air passing upward, in most instances, at three of the sides thereof, the air taking up the heat radiated from lugs. The heat imparted to the bars will also be absorbed by the air in like manner, so that the whole grate will be effectively cooled, or be kept from being overheated by the air which is drawn, or forced up thru the grate to support combustion. The air will in this manner also be effectively pre-heated before it becomes mixed with the gas from the fuel, so that the efficiency of combustion will be thereby greatly increased. While there is a practical limit to the extent to which it is desirable to have the projections 23 extend above the level of the 70 top of the grate bars, the extent indicated in the drawings is desirable, but may be somewhat varied according to conditions.

As the adjacent sides of the lugs on the sides of the bars diverge from the tops of the bars downward, the air passages therebetween are contracted as they extend upward, so that the air is somewhat concentrated into jets at the points at which it is delivered to the fuel, and these jets are immediately diffused or expanded beneath the fuel between the projections 23 and over the top sides of the bars. As the sides of the projections 23 converge as they extend upward from the tops of the bars, and the tops of the projections are small, the ash which may accumulate thereon will readily fall into the ash pit thru the spaces between the lugs and the bars, this action being greatly assisted by a slight jarring action 95 of the grate.

It has been demonstrated in practice that, with this construction, a greatly increased rate of fuel combustion is secured, with a corresponding increase in evaporation capacity, this being principally due to the greatly increased volume of air which is supplied to the whole fuel mass. A relatively high heat is, in consequence, secured at the surface of the fuel mass, with the further result that material carrying a low percentage of carbon is disintegrated and materials carrying no carbon, such as slate, are highly heated, so that as these materials sink down close to grate and the relatively cool air comes in contact therewith, they crumble, so that they pass readily thru the grate. The formation of clinkers is almost entirely prevented for similar reasons.

The combustion materials in the fuel are practically entirely consumed, as the percentage of unburned combustible in the ash is found to be inconsequential, being confined to small particles which fall thru the 125 grate.

In consequence the grate becomes freed from noncombustible material, either automatically, or by a slight jarring action on the grate, so that dumping or otherwise cleaning the grate is only necessary after 5 long periods of use.

The construction shown permits the grate to be tilted, to shake it, or dump the fuel thereon, but it will be understood, however, 10 that my invention is not necessarily limited to dumping forms of grates, but may be employed in connection with grates of other types.

I claim:

15 1. A fuel grate comprising a series of suitably spaced horizontally disposed bars, each bar having a series of suitably spaced lugs projecting laterally from one side thereof, to provide vertically extending air passages 20 between the adjacent sides of the lugs at the side of the bar and between the ends of the lugs and the next adjacent bar, each of said lugs being extended above the level of the top of the bar and having fuel supporting 25 faces on their upper ends.

2. A fuel grate comprising a series of suitably spaced horizontally disposed bars, each bar having a series of suitably spaced lugs projecting laterally from each side thereof, 30 to provide vertically extending air passages at each side of the bar between the adjacent sides of the lugs and between the ends of the lugs and the next adjacent bars, each of said lugs being extended above the level of the top 35 of the bar and having fuel supporting faces on their upper ends.

3. A fuel grate comprising a series of suitably spaced horizontally disposed bars, each bar having a series of suitably spaced lugs 40 projecting laterally from one side thereof and extending from the bottom to the top of the bar, to provide vertically extending air passages at the side of the bar between the adjacent sides of the lugs and between the 45 ends of the lugs and the next adjacent bar, each of said lugs being extended above the level of the top of the bar and having fuel supporting faces on their upper ends.

4. A fuel grate comprising a series of suitably spaced horizontally disposed bars, each bar having a series of suitably spaced lugs 50 projecting laterally from each side thereof and extending vertically from the bottom of the bar to a level above the level of the top 55 of the bar and having fuel supporting faces at their upper ends, to permit the free circulation of air between the adjacent sides of the lugs and between the ends of the lugs and the adjacent bars thereby to take up heat 60 conducted from the top ends of the lugs to their lower portions.

5. A fuel grate comprising a series of suitably spaced horizontally disposed bars, each bar having a series of suitably spaced lugs 65 projecting laterally from one side thereof, to

provide vertically extending air passages between the adjacent sides of the lugs at the side of the bar and between the ends of the lugs and the next adjacent bar, each of said lugs being extended above the level of the 70 top of the bar and having fuel supporting faces on their upper ends and the sides of said lugs being arranged to extend convergently downward from the top of the bar.

6. A fuel grate comprising a series of 75 spaced, horizontally disposed bars, each bar having a series of lugs projecting from each side thereof from top to bottom in opposite relation, the lugs of each bar being spaced uniformly from each other and from the adjacent lugs of the next adjacent bar, and being extended vertically above the level of the bars, to form projections, said projections having fuel-supporting faces at their upper ends disposed at an approximately uniform 80 level, whereby vertically extending air 85 passages are provided at the three sides of each lug and its projection and a horizontally extending passage is provided between the opposite projections of each lug, which open to 90 said air passages at each end.

7. A fuel grate comprising a series of 95 spaced, horizontally disposed bars, each bar having a series of lugs projecting horizontally from each side thereof, said lugs being 100 spaced apart and terminating at a distance from the adjacent bars to provide air passages at each side and the ends thereof, and a projection extending vertically from the upper side of each lug with its sides extending continuously therewith at three sides and with its fourth side extending from the upper surface of the bar adjacent the line of its edge, and said projections having fuel-supporting faces at their upper ends.

8. A fuel grate comprising a series of 105 spaced, horizontally disposed bars, each bar having a series of lugs projecting horizontally from each side and vertically from bottom to top thereof in opposite relation, said lugs being spaced from each other and from the lugs of the adjacent bars at their ends and each lug having a projection extending vertically from the upper portion thereof above the level of the upper surfaces of the 110 bars, each projection having a fuel-supporting face at its upper end.

9. A fuel grate comprising a series of 115 parallel, horizontally disposed and uniformly spaced bars, each bar having a series of 120 uniformly spaced lugs projecting horizontally from each side thereof, each opposite pair of lugs being in alignment with each other and with a corresponding pair of lugs of the other bars and the adjacent lugs of the next 125 adjacent bars being spaced apart at their ends, each lug having a projection formed continuously therewith and extending vertically from the upper portion thereof, above the level of the upper surfaces of the bars, 130

- the opposite projections of each bar being spaced apart by approximately the width of the bar and said projections having fuel-supporting faces at their upper ends.
5. 10. A fuel grate comprising a frame having a series of regularly spaced, inwardly projecting lugs extending about the inner edge thereof, said lugs having upwardly extending projections having fuel-supporting faces at their upper ends disposed above the level of the grate, a plate mounted within the frame and comprising longitudinal and transverse bars having similarly spaced lugs projecting from each side thereof and projections extending vertically from said lugs above the level of said bars and having fuel-supporting faces at their upper ends. 70
10. 15. A fuel grate comprising a frame having a series of regularly spaced, inwardly projecting lugs extending about the inner edge thereof, said lugs having upwardly extending projections having fuel-supporting faces at their upper ends disposed above the level of the grate, a plate mounted within the frame and comprising longitudinal and transverse bars having similarly spaced lugs projecting from each side thereof and projections extending vertically from said lugs above the level of said bars and having fuel-supporting faces at their upper ends. 75
15. 20. A fuel grate bar having a horizontally disposed top surface and a series of suitably spaced lugs projecting laterally from one side of the bar and extending downward from said surface, providing a vertically extending air passage between adjacent lugs, each of said lugs having a projection thereon which extends continuously therewith above the level of said top surface and is provided with a fuel-supporting face on its top. 80
20. 25. A fuel grate bar having a horizontally disposed top surface and a series of suitably spaced lugs projecting laterally from one side of the bar and extending downward from said surface, providing a vertically extending air passage between adjacent lugs, each of said lugs having a projection thereon which extends continuously therewith above the level of said top surface and is provided with a fuel-supporting face on its top. 85
25. 30. A fuel grate bar having a horizontally disposed top surface and a series of suitably spaced lugs projecting laterally from both sides thereof and extending downward from said surface, providing vertically extending air passages between adjacent lugs, each of said lugs having a projection thereon which extends continuously therewith above the level of said top surface and has a fuel-supporting face on its top, and all of said projections being spaced apart to permit the passage of air entirely about the same. 90
30. 35. A fuel grate bar having a horizontally disposed top surface and a series of suitably spaced lugs projecting laterally from both sides thereof and extending downward from said surface, providing vertically extending air passages between adjacent lugs, each of said lugs having a projection thereon which extends continuously therewith above the level of said top surface and has a fuel-supporting face on its top, and all of said projections being spaced apart to permit the passage of air entirely about the same. 95
35. 40. A fuel grate bar having a horizontally disposed top surface and a series of suitably spaced lugs projecting laterally from both sides thereof and extending downward from said surface, providing vertically extending air passages between adjacent lugs, each of said lugs having a projection thereon which extends continuously therewith above the level of said top surface, all of said projections being spaced apart to permit the passage of air entirely about the same and having fuel-supporting faces at their tops disposed at approximately the same level. 100
40. 45. A fuel grate bar having a horizontally disposed top surface, a series of integrally formed lugs projecting laterally from each side thereof in spaced relation and extending downwardly from its top surface and upwardly from said surface to form projections having fuel-supporting faces at their tops, each projection being formed to taper from said surface to its top and having its sides continuous with the sides of its corresponding lug. 105
45. 50. A fuel grate bar having a horizontally disposed top surface, a series of integrally formed lugs projecting laterally in spaced relation from one side of the bar and extending downwardly from its top surface and having integrally formed projections extending upwardly from said surface, said projections having fuel-supporting faces at their top ends and said lugs being formed to taper downward and said projections to taper upwardly from said surface, providing air passages between adjacent lugs, the sides of which converge to the top of the bar and diverge above the bar. 110
50. 55. A fuel grate bar having a horizontally disposed top surface and a series of lugs projecting laterally therefrom in spaced relation, and formed integrally therewith, each lug being extended downwardly from a level adjacent said surface and having an integral projection extending upwardly from said level and provided with a fuel-supporting face at its top, the corresponding sides of each lug and its projection being continuously formed and the opposite sides thereof being tapered oppositely from said level to its end, to provide vertically extending air passages between adjacent lugs and projections the sides of which converge to said level and diverge from said level as they extend upwardly. 115
55. 60. A fuel grate comprising a series of horizontally disposed bars arranged in parallelism each bar having a series of integrally formed lugs projecting laterally from each side in spaced relation and extending downwardly from its top surface and upwardly from said surface to form projections having fuel-supporting faces at their tops, the sides of each lug and its projection being oppositely tapered from said surface, and said bars being arranged to provide air passages between the outer sides of the lugs on each bar and the lugs on the next adjacent bars. 120
60. 65. A fuel grate bar which comprises a longitudinal member, cross bars extending from said member, a plurality of spaced lugs projecting laterally from both sides of said cross bars and extending downwardly from the top thereof to provide vertical air passages between adjacent lugs, and projections extending upwardly from said lugs and having flat tops lying above the top of said cross bars, the flat tops of said projections forming a fuel supporting surface, said projections being spaced apart to permit air from said passages to flow between said projections to the fuel supported thereon. 125
65. 70. In a fuel grate bar, the combination of a longitudinal member, cross bars extending from said member, a plurality of spaced lugs projecting laterally from both sides of said cross bars, adjacent lugs in part defining vertical air passages, and projections extending upwardly from said lugs, each projection terminating in a flat fuel supporting surface of less area than the average cross-sectional 130

area of the projection, said surfaces lying above the top of said cross bars and said projections being spaced to permit air from said passages to flow between said projections to the fuel supported thereon.

5 In testimony whereof, I have signed my name to this specification.

JOHN J. BUCKLEY.
